MEASURING DEVICES FOR RAILWAY TRACKS**Stafford Malcolm Ellis, Potters Bar, England, assignor to Elliott Brothers (London) Limited, London, England****Application September 16, 1957, Serial No. 684,090****Claims priority, application Great Britain September 18, 1956****11 Claims. (Cl. 33—144)**

This invention relates to measuring devices for railway tracks and particularly to railway track testing apparatus of the kind in which a probe carried on a car movable along the track is held in engagement with the side face of a running rail so that defects such as waves and kinks, and also curvature of the rail will cause a corresponding movement of the probe which may be recorded by appropriate apparatus carried on the car.

Hitherto and in order to avoid difficulties occasioned by gaps, points and other hazards of the track, such arrangements have used a probe having a long shoe held in contact with the rail. Because the whole arrangement is cumbersome and heavy it is insensitive to small variations in the shape of the rail and the shoe is subject to rapid wear.

It is accordingly an object of the present invention to provide an arrangement which enables a probe having a comparatively small shoe to be used and which is accordingly lighter and more sensitive. A probe having such a small shoe can be arranged to make a substantially point contact rather than a line contact with the rail and it is practical to provide it with a working face formed of a special hard wearing material such as a suitable grade of hard metal.

However, such a small probe cannot unaided pass safely along the flange ways of a track and through the various hazards that are encountered and accordingly in the improved arrangement of this invention the movement of this probe, the measuring probe, is controlled by a guide probe which is arranged in staggered relationship with respect to the measuring probe and is adapted to be engaged by the outer side face of a guard or check rail associated with the running rail opposite to that which is engaged by the measuring probe.

By means of such an arrangement the measuring probe will be held on a safe path as it travels through the various hazards likely to be encountered and in particular will be restrained against outward movement when gaps occur in the rail being examined.

Conveniently each probe is carried on an arm which depends from a member which is slidably mounted in bearings on the car for movement on a transverse horizontal axis. In such case, and in order to provide compensation for the effects of curvature of the track, the two members are conveniently connected by means of links with spaced points on a lever, one end of which is pivotally mounted on the car and which extends horizontally and generally parallel with the longitudinal axis of the car.

Spring or other means may be provided to bias the measuring probe so that its shoe is normally held in contact with the running rail. The shoe of each probe may conveniently be resiliently mounted as, for example, by means of leaf springs so that it may flex relative to its mounting about a vertical axis. The shoe of the measuring probe is preferably somewhat dished or rounded in section so that it can slide easily over irregularities in the rail while that of the guide probe is of similar shape

2

but double sided since it may on occasion engage either the running rail on one side or a guide rail on its other side.

The mechanism may also include means which is effective to produce a change in the spacing of the two probes when the apparatus is negotiating spring catch points or other hazards through which the guide probe may be ineffective in steering the measuring probe. Means may also be provided for retracting the probes when they are not in use.

The use of a guide probe for controlling the mechanism of the invention enables the measuring probe to have only a relatively small shoe, since, for example, when the apparatus is negotiating an acute crossing, the engagement of the guide probe with the guard rail holds the measuring probe on the right path. Obtuse crossings may also be safely negotiated because the guide probe is staggered relatively to the measuring probe while the linkage connecting them together provides the necessary compensation for the staggering of the two probes when the apparatus is negotiating curves.

It will be appreciated that the movement of the measuring probe relative to the car on which it is mounted will in practice be communicated by any suitable mechanical or electric means to measuring or recording apparatus.

In order that the invention may be clearly understood it will now be described with reference to the accompanying drawings, in which:

30 Figure 1 is a diagrammatic plan view showing one form of an arrangement comprising a measuring probe and a guide probe,

Figure 2 is a diagrammatic perspective view from below showing one form of an arrangement comprising 35 two measuring probes and their associated guide probes.

Figure 3 is a plan view of the arrangement of Figure 2,

Figure 4 is an end view looking in the direction of the arrow 4 in Figure 3,

40 Figures 5 and 6 are a side view and plan respectively on a larger scale showing the measuring probe shoe indicated by the arrow 5 in Figure 4, and

Figures 7 to 9 are sections on the lines VII—VII, VIII—VIII and IX—IX of Figure 3.

45 Referring now to Figure 1, there is shown a diagrammatic plan view of an arrangement comprising a measuring probe 10 which is carried on a rod 11 slidably mounted in a bearing 12 secured with the body of a car 13, and a guide probe 14 which is similarly carried on a rod 15 slidably mounted in bearings 16. As shown,

50 the inner end of the rods 11 and 15 are pivotally connected at spaced points on a lever 17 which is itself pivotally connected at 18 with the body of the car 13. The measuring probe 10 is biased outwardly of the car body by a spring 19 so that it is normally held in engagement with the inner face of the running rail and the movement of this probe relative to the car body is applied by a link 20 to operate a suitable form of transducer 21 which provides, for example, an electric signal

55 proportional to the movement of the probe. In operation, the measuring probe 10 lies with its working face pressed against the inner face of one running rail of the track but since the probe face is relatively short, being only some two or three inches long instead of about three feet long as in prior arrangements, it would foul the various hazards along the track were it not for the guide probe 14 whose function it is to steer the measuring probe along a safe path, for example the guide probe prevents the measuring probe moving outwardly 60 under the influence of the spring 19 when a gap occurs in the running rail. This the guide probe achieves since it will then be engaged by the outer face of the guard rail

65

which, at least in the British Railway System, is always present where hazards occur. This function of the guide probe could, however, not be accomplished if the two probes were arranged opposite to one another and it is an essential feature of the arrangement that one probe is in advance of the other. The amount of stagger required is a matter which can be determined by analysis of the various types of hazard normally encountered.

Figure 1 illustrates an obtuse crossing which is typical of a hazard that to a large extent determines the amount of stagger which is required. As may be seen from the drawing, the chain dotted lines indicate the flange ways and not the rails themselves, the guide probe 14 is holding the measuring probe from moving outwards until such time as it engages the face 22 of a running rail, at which time the guide probe will leave the face 23 of the guard rail. It is assumed in this example that the car is moving to the right in the drawing. It will be appreciated that under normal conditions when the measuring probe is engaging the running rail under examination, its connection with the guide probe will be such that this guide probe will be caused to run in the flangeway between the other running rail and the guard rail if one is present without contacting either of them. It is only, for example, when a gap occurs in the rail under examination that the guide probe comes into operation and prevents, by engagement with the guard rail, outward movement of the measuring probe.

A further factor in the design of this arrangement is the lever 17. If the probe system could be mounted symmetrically about the central transverse axis of the car this lever would not be required and a simple link between the two probe arms would suffice. However, since in any recording car there will be more than one such set of probes and since only one of these sets could be mounted in the central position, the other sets have to be arranged either fore or aft of the central transverse axis and compensation has to be provided for the varying distances between the rails as measured along a transverse axis of the car as it goes round a curve. Such compensation is provided by connecting the probe arms 11 and 15 at spaced points on the lever 17 which itself is pivotally mounted at its end on the car. With such an arrangement, when the car is on a curved section of the track the inclination of the lever 17 with respect to the central longitudinal axis of the car will change and this will vary the space between the two probes as measured in a direction transversely of the car. Accordingly, while the measuring probe is in contact with the rail under examination, the guide probe will be held in the correct position adjacent the other running rail and between it and the guard rail if one is present.

In carrying the invention into effect, means must be provided for retracting the probes towards one another and for raising them clear of the rails. One arrangement offering such facilities and providing also two measuring probes each with its associated guide probe is shown in Figures 2 to 9. The arrangement provides two measuring probes 25 and 26 one for each running rail and their associated guide probes 27 and 28 respectively. Each probe is carried on an arm 29 which extends vertically downwards from a pneumatic or hydraulic jack 30 by means of which the probe may be drawn upwards away from the track. Normally the jack will operate by means of fluid pressure to hold the probes in their operative positions and they will be retracted from this position by spring action.

In addition, and in order that the probes may be moved inwardly away from contact with the rails, the jacks controlling the measuring probes 25 and 26 are slidably mounted on two vertically spaced horizontal rods 31 and 32 while the jacks controlling the guide probes 27 and 28 are similarly mounted on two rods 33 and 34. The four rods 31 to 34 are secured at their ends on plates 35 and 36 which in turn are attached to the frame

of the car in such a manner that twisting of the car frame will not distort the rod plate assembly. To this end the plate 36 is formed with two lugs 38 and 39 which are pivotally received in brackets 40 and 41 secured with the car frame, and plate 35 is formed with a single lug 42 which is pivotally received in a bracket 43 secured with the other side of the car frame. The three-point mounting thus provided for the rod plate assembly ensures that while it is held in the required position it can move relative to the car frame if this frame twists, that is to say if one side of the frame rises or falls relative to the other.

The jack carrying the measuring probe 25 is connected by a link 45 with the free end of a lever 46 which is pivotally mounted at the other end 47 in a frame 48 carried on the rods 31 to 34, and this link is provided with a turnbuckle device 49 whereby its length can be adjusted. The associated guide probe 27 is also connected with lever 46 by means of a guide link 50. The lever 46 is biased in the direction to hold the measuring probe 25 against the running rail by means of a tension spring 51 and a pneumatic or hydraulic jack 52 is provided for centering the lever 46 when it is required to move the measuring probe away from the rail. The other measuring probe 26 and its guide probe 28 are connected in exactly the same way with a lever 53 which in turn can be centered by a jack 54 so as to withdraw the measuring probe 26 away from its running rail. It will be appreciated, however, that the centering of lever 46, for example, to withdraw the measuring probe 25, would have the effect of moving the associated guide probe 27 outwards if link 50 were a rigid connection. To avoid this difficulty this guide probe is also connected with the lever 53 by a centering link 55. The links 50 and 55 are similar in construction in that they are telescopic, but while link 50 is normally extended to its maximum length by the spring 56 which surrounds it to keep guide probe 27 from sliding towards the center of the car where it would not be able to engage the guard rail, the link 55 has no spring and is normally not quite fully extended when it is in the position shown. In normal operation, therefore, the link 50 will transmit the movement of the guide probe 27 to control the position of the measuring probe 25. However, when both levers 46 and 53 are centered by the action of the jacks 52 and 54, the movement of lever 53 will cause the guide probe 27 to be drawn inwards by link 55 and link 50 will be compressed against its spring 56. The guide probe 28 is similarly connected with the levers 46 and 53 and is operated in the same way.

The construction of the links 45, 50 and 55 is shown in greater detail in Figures 7 to 9 respectively.

As shown in Figure 7, the link 45 comprises two rods 58 and 59, the adjacent ends of which are oppositely threaded and are received in the appropriately threaded ends of a sleeve 60, nuts 61 being provided to lock the rods with the sleeve after the length of the link has been adjusted as required by rotation of the sleeve relative to the rods.

The guide link shown in Figure 8 comprises a tubular member 62 in which is received an end of a rod 63 which is formed with spaced raised lands 64 that engage the wall of the tubular member and the right hand one of which, as shown in the drawing, serves, in conjunction with a cap 65 screwed on the end of the tubular member 62, as a stop to limit the extension of the link. A spring 66 surrounds the tubular member 62 and rod 63 and urges these parts into a position of maximum extension.

The centering link 55 shown in Figure 9 is generally similar to the link 50 of Figure 8 and comprises tubular member 66 and rod 67, the cap 68 of member 66 serving in conjunction with the raised land 69 on the rod 67 as a stop to limit extension of the link but in this case there is no external spring.

Figures 5 and 6 show the construction and shape of

the wearing shoes of the measuring probes 25 and 26 and it will be seen, especially from the plan view of Figure 6, that the actual surface in contact with the rail is quite short, being in practice of the order of three inches, while the total length of the shoe is only of the order of ten inches.

The shoe may be resiliently attached to the arm 29 of the associated jack if desired. Alternatively, or in addition, the jack itself may be resiliently mounted in its supporting cage. The wearing shoe of the guide probes is similar in shape but is double sided since this shoe has to engage both the guard rail and the adjacent running rail.

What I claim is:

1. Railway track testing apparatus comprising a car, a measuring probe mounted on said car for movement on an axis transverse to said car, means normally biasing said measuring probe into contact with the inner side face of one of the running rails, a guide probe mounted on said car for movement on an axis transverse to said car and longitudinally spaced from said first-mentioned transverse axis, said guide probe extending between the inner side face of the other running rail and the outer face of a guard rail associated therewith, and means operatively connecting said measuring probe and said guide probe comprising a lever pivotally mounted at one end on said car and extending in a longitudinal direction thereof, and means connecting said measuring probe and said guide probe with respective longitudinally spaced points on said lever.

2. Railway track testing apparatus comprising a car, a measuring probe assembly slidably mounted on said car for movement on an axis transverse to said car, said assembly including a downwardly depending arm and a probe shoe mounted on the lower end of said arm, means for biasing said assembly to hold said shoe in contact with the inner side face of a running rail, a guide probe assembly slidably mounted for movement on an axis transverse to said car, said transverse axis being longitudinally spaced from the first-mentioned transverse axis, said guide probe assembly including a downwardly depending arm and a probe shoe mounted on the lower end of said arm and positioned between the inner side face of the other running rail and the outer side face of a guard rail associated therewith, and means operatively connecting said probe assemblies comprising a lever pivotally mounted at one end on said car and extending longitudinally thereof, a first link connecting said measuring probe assembly with a first point on said lever, and a second link connecting said guide probe assembly with a second point on said lever, said first and second points being longitudinally spaced from one another.

3. Railway track testing apparatus as claimed in claim 2, in which each guide probe assembly includes means for raising the probe shoe relative to the associated rail.

4. Railway track testing apparatus comprising a car, a first and a second measuring probe assembly each including a downwardly depending arm and a probe shoe mounted on the lower end of said arm, means on said car on which each said probe assembly is slidably mounted for movement on a common axis to said car, means on said car for biasing each said probe assembly such that its probe shoe is held in contact with the inner side face of the respective running rail, a first and a second guide probe assembly each including a downwardly depending arm and a probe shoe mounted on the lower end of said arm, said first and second guide probe assemblies being normally positioned to hold their respective probe shoes adjacent the running rails engaged by the probe shoes of said second and said first measuring probe assemblies respectively, means on said car on which each said guide probe assembly is slidably mounted for movement on a common axis transverse to said car and which is spaced from said first-mentioned transverse axis, a first and a second lever each pivotally mounted at one end on

said car and extending longitudinally thereof in the same direction, a first pair of links connecting said first measuring probe assembly and said first guide probe assembly to respective longitudinally spaced points on said first lever, and a second pair of links connecting said second measuring probe assembly and said second guide probe assembly to respective longitudinally spaced points on said second lever.

5. Railway track testing apparatus as claimed in claim 4, in which the means for slidably mounting the first and second measuring probe assemblies and the first and second guide probe assemblies each comprises a pair of vertically spaced rods extending transversely of the car, each said assembly having spaced tubular bushings through which said pair of rods extends.

6. Railway track testing apparatus as claimed in claim 5, in which said means for slidably mounting said first and second measuring probe assemblies further comprises two plate-like members secured respectively with each end of each of said rods, said plate-like members being hingedly connected with said car for movement about respective longitudinal axes of the car.

7. Railway track testing apparatus as claimed in claim 4, in which each said probe assembly comprises a fluid-operated jack having a downwardly directed plunger constituting the said arm on the end of which the said probe shoe is mounted.

8. Railway track testing apparatus as claimed in claim 4, in which said means for slidably mounting said first and second measuring probe assemblies further comprises means for retracting the probe shoes away from the rails and towards the center of the track.

9. Railway track testing apparatus comprising a car, a first and a second measuring probe assembly each including a downwardly depending arm and a probe shoe mounted on the lower end of said arm, means on said car on which each said probe assembly is slidably mounted for movement on a common axis transverse to said car, means for biasing each said probe assembly such that its probe shoe is held in contact with the inner side face of the respective running rail, a first and a second guide probe assembly each including a downwardly depending arm and a probe shoe mounted on the lower end of said arm, said first and second guide probe assemblies being normally positioned to hold their respective probe shoes adjacent the running rails engaged by the probe shoes of said second and said first measuring probe assemblies respectively, means on said car on which each said guide probe assembly is slidably mounted for movement on a common axis transverse to said car

45 which is spaced from said first-mentioned transverse axis, a first and a second lever each pivotally mounted at one end on said car and extending longitudinally thereof in the same direction, a first pair of links connecting said first measuring probe assembly and said first guide probe assembly with respective longitudinally spaced points on said first lever, a second pair of links connecting said second measuring probe assembly and said second guide probe assembly with respective longitudinally spaced

50 points on said second lever, means on said car for retracting the several probe shoes away from the running rails and towards the center of the track including means for moving said first and second levers about their pivot points, a pair of centering links for transmitting tension

55 only connecting respectively the said first lever with said second guide probe assembly and said second lever with said first guide probe assembly, the said pair of links connecting respectively the first lever and first guide probe assembly and the second lever and second guide probe assembly having compressible spring means therein.

60 10. Railway track testing apparatus as claimed in claim 9, in which said means on which said probe assemblies are mounted each include two plate-like members pivotally mounted on respective sides of said car for movement about respective longitudinal axes, a first and a

65 second lever each pivotally mounted at one end on

second pair of vertically spaced rods constituting said spaced transverse axes, said rods extending between said plate-like members and rigidly secured thereto, said probe assemblies having tubular bushings thereon, a pair of rods passing through said bushings, and a frame mounted centrally on said rods and having a pivot point thereon for said first and second levers.

11. Railway track testing apparatus as claimed in claim 10, including fluid-operated jacks for moving said levers to retract the probe shoes, said jacks being mounted on 10 said frame.
